(57) **CLAIM**

The ornamental design for a portion of display panel or screen with an icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display panel or screen with icon showing our new design;

FIG. 2 is a second embodiment thereof.

FIG. 3 is a third embodiment thereof.

FIG. 4 is fourth embodiment thereof.

FIG. 5 is a fifth embodiment thereof.

FIG. 6 is a sixth embodiment thereof.

FIG. 7 is a seventh embodiment thereof.

FIG. 8 is an eighth embodiment thereof.

FIG. 9 is a ninth embodiment thereof.

FIG. 10 is a tenth embodiment thereof.

FIG. 11 is an eleventh embodiment thereof.

FIG. 12 is a twelfth embodiment thereof.

FIG. 13 is a thirteenth embodiment thereof.

FIG. 14 is a fourteenth embodiment thereof.

FIG. 15 is a fifteenth embodiment thereof.

FIG. 16 is a sixteenth embodiment thereof.

FIG. 17 is a seventeenth embodiment thereof; and,

FIG. 18 is an eighteenth embodiment thereof.

The dot-dash broken lines at the perimeter of each figure (including the perimeter of the black shaded icon of FIG. 7) illustrate a portion of a display panel or screen and define the
